CLAIM

The ornamental design for a door bin for refrigeration machines and apparatus as shown and described.

DESCRIPTION

1. Door bin for refrigeration machines and apparatus

1.1 : Perspective

1.2 : Front

1.3 : Right

1.4 : Back

1.5 : Left

1.6 : Top

1.7 : Bottom

1. Title of the product incorporating the design: Door bin for refrigeration machines and apparatus; 2. Use of the product incorporating the design: Use as a door bin for refrigeration machines and apparatus; 3. Essential features of the design: As shown by the shapes of Design 1; 4. Photograph design-
